ARTICLE OF REPOSE FOR SUPPORTING THE BODY OF A PERSON

Anton Lorenz, Ocean Ridge, Fla.

Application April 23, 1954, Serial No. 425,096

9 Claims. (Cl. 155—106)

This invention relates to articles of furniture and more particularly to articles of repose for supporting the body of a person wherein a back-rest and a seat pivoted to said back-rest are connected with each other through a link system whereby coordinated movements of the back-rest and the seat are obtained.

An object of the invention is to provide an improved link system for this type of articles of repose.

Another object of the invention is to provide means for controlling the movements of the leg-rest swingably mounted on the seat of such an article of repose.

A further object of the invention is to improve on the construction of articles of repose as now customarily made.

Other objects and structural details of the invention will be apparent from the following description when read in conjunction with the accompanying drawings forming part of this specification, wherein:

Fig. 1 is a side elevational view of a reclining chair according to the invention, a portion of a side frame being broken away,

Fig. 2 is a side elevational view of the reclining chair shown in Fig. 1, wherein however the movable members of the chair are in the extreme reclined position,

Fig. 3 is a side elevational view of another embodiment of a reclining chair according to the invention, a portion of a side frame being broken away,

Fig. 4 is a side elevational view of a further embodiment of a reclining chair according to the invention, a portion of a side frame being broken away,

Fig. 5 is a side elevational view of still another embodiment of the chair according to the invention, a portion of a side frame being broken away, and

Fig. 6 is a side elevational view of a further embodiment of a reclining chair according to the invention, a portion of a side frame being broken away.

Referring now to Figs. 1 and 2, 10 generally indicates a support comprising side frames 12 and 14 connected with each other by a cross bar 16.

The lower end of a back-rest 18 is swingably mounted on the support 10 at 29. The rear end portion of a seat 22 is pivoted to said back-rest 18 at 24 at a point above the pivotal connection 20 between the back-rest 18 and the support 10.

A controlling element 26 in the shape of a bell-crank lever is swingably mounted on the support 10 at 28. The upper arm 30 of said controlling element 26 is pivoted at 32 to the front end portion of a connecting link or arm-rest 34. The rear end portion of said connecting link 34 is pivoted to the back-rest 18 at 36 at a point above the pivotal connection 24 between the back-rest 18 and the seat 22. The lower arm 38 of the controlling element 26 is pivoted at 40 to the lower end of a link 42, the upper end of which is pivoted to the seat 22 at 44.

A leg-rest 46 swingably mounted on the front end portion of the seat 22 at 48 is pivoted to the front end of a controlling link 50 at 52. The rear end of said controlling link 50 is pivoted at 54 to the lower end of an arm 56

swingably mounted on the seat 22 at 58. One end of a link 60 is pivoted to said arm 56 at 62, the other end of said link 60 is pivoted to the lower arm 38 of the controlling element 26 at 40 in coaxial alignment with the pivotal connection between said lower arm 38 and the link 42.

When the back-rest 18 is moved from the sitting position, shown in Fig. 1, into the reclined position 18', shown in Fig. 2, the seat and the leg-rest are brought into the positions 22' and 46' respectively by means of above described link system.

The sitting position of the movable members of the chair, shown in Fig. 1, is limited by a stop 64 arranged on the support for abutting cooperation with the seat 22. The extreme reclined position of the movable members of the chair, shown in Fig. 2, is limited by another stop 66 arranged on the support for abutting cooperation with the lower end of the back-rest 18.

According to the embodiment shown in Fig. 3, again 20 the back-rest 118 is swingably mounted on the support 110 at 120 and the rear end of the seat 122 is pivoted to the back-rest 118 at 124 at a point above the pivot 126 of the back-rest 118. Furthermore, again the controlling element 126 swingably mounted on the support 110 at 128 is controlled by the connecting link 134 pivoted to the upper arm 130 of the controlling element 126 and to the back-rest 118 at the points 132 and 136 respectively.

The controlling mechanism for the seat 122 however is 30 different. According to Fig. 3, an arm 168 is swingably mounted on the support 110 at 170. A link 172 is pivoted at different regions thereof to the lower arm 138 of the controlling element 126 at 141 and to said swingable arm 168 at 174. The seat 122 is pivoted to the upper end of 35 a link 143 at 144. The lower end of said link 143 is pivoted to the swingable arm 168 at 176.

The leg-rest 146 swingably mounted on the front portion of the seat 122 at 148 is pivoted to one end of the 40 controlling link 150 at 152. The other end of said controlling link 150 is pivoted to the swingable arm 168 at 155.

The sitting position of the movable members of the chair, shown in full lines, is limited by the stop 164 and the extreme reclined position of the movable members of the chair, shown in dash-and-dot lines, is limited by the stop 166.

According to the embodiment shown in Fig. 4, the backrest 218 swingably mounted on the support 210 at 220 is pivoted to the rear end of the seat 222 at 224 and to the rear end of the connecting link 234 at 236. The upper arm 230 of the controlling element 226 swingably mounted on the support 210 at 228 is pivoted to the connecting link 234 at 232. The lower arm 238 of said controlling element 226 is pivoted at 241 to one end of the link 272. The other end of said link 272 is pivoted at 274 to an arm 268 swingably mounted on the support 270. Said swingable arm 268 has an extension 278 rigid therewith. A roller 280 rotatably mounted on said extension 278 is in movable abutting engagement with the lower surface of the seat 222.

The leg-rest 246 swingably mounted on the front portion of the seat 222 at 248 is pivoted at 252 to one end of the controlling link 250. The other end of said controlling link 250 is pivoted at 255 to the swingable arm 268.

The sitting position of the movable members of the chair, shown in full lines, is limited by a stop 264 arranged on the support 210. The extreme reclined position of the movable members of the chair, shown in dash-and-dot lines, is limited by a stop 266 also arranged on the support 210.

According to the embodiment shown in Fig. 5, again

the lower end of the back-rest 318 is swingably mounted on the support 310 at 320. The rear end portion of the seat 322 is pivoted to the back-rest 318 at 324 at a point above the pivotal connection 320 of the back-rest 318 with the support 310. The rear end of the connecting link or arm-rest 334 is pivoted to the back-rest 318 at 336 at a point above the pivotal connection 314 between the back-rest 318 and the seat 322. The upper arm 330 of the controlling element 326 swingably mounted on the support 310 at 328 is pivoted to the connecting link 334 at 332. The lower arm 338 of said controlling element 326 carries a roller 382 being in abutting engagement with an arm 368 swingably mounted on the support 310 at 370. A link 343 is pivoted at different regions thereof to said swingable arm 368 at 376 and to the seat 322 at 344. The controlling link 350 is pivoted at different regions thereof to said swingable arm 368 at 355 and to the leg-rest 346 at 352. The leg-rest 346 is swingably mounted on the front portion of the seat 322 at 348.

The sitting position of the movable members of the chair, shown in full lines, is limited by the stop 364 and the extreme reclined position of the movable members of the chair, shown in dash-and-dot lines, is limited by the stop 366.

According to the embodiment shown in Fig. 6, again the back-rest 418 is pivoted at three different points 420, 424 and 436 respectively to the support 410, the seat 422 and the connecting link 434 respectively. The upper arm 430 of the controlling element 426 swingably mounted on the support 410 at 428 is pivoted to the connecting link 434 at 432. The lower arm 438 of the controlling element 426 has an extension 484 rigid therewith. Said extension 484 carries a roller 486 arranged for abutting engagement with the lower surface of the seat 422.

The leg-rest 446 swingably mounted on the front portion of the seat 422 at 448 is pivoted to one end of the controlling link 450 at 452. The other end of said controlling link 450 is pivoted to the lower arm 438 of the controlling element 426 at 453.

The sitting position of the movable members of the chairs shown in full lines, is limited by the stop 464 and the extreme reclined position of the movable members of the chair, shown in dash-and-dot lines, is limited by the stop 466.

I have described preferred embodiments of my invention, but it is understood that this disclosure is for the purpose of illustration, and that various changes in shape, proportion of parts, as well as the substitution for equivalent elements for the arrangements shown and described may be made without departing from the spirit and scope of the invention as set forth in the appended claims.

Each of the embodiments of a reclining chair according to the invention may be equipped with locking means for holding the movable members of the chair in any desired position.

What I claim is:

1. An article of repose for supporting the body of a person, comprising in combination: a support, a back-rest pivoted to said support, a seat, the rear end portion of said seat being pivoted to said back-rest at a point above the plane of the pivotal connection between the back-rest and the support, a controlling element pivoted intermediate its ends on said support, a connecting link pivoted at different regions thereof to said controlling element at one side of its pivotal connection to said support and to said back-rest at a point above the pivotal connection between said back-rest and said seat, and controlling means interposed between said controlling element at the other side of its pivotal connection to said support and said seat for effecting movements of said seat in coordination with movements of said controlling element, a leg-rest swingably mounted on the front portion of the seat, an arm swingably mounted on said seat, a first link pivoted at different regions thereof to said controlling element and to said arm, and a second link

pivoted at different regions thereof to said arm and to said leg-rest.

2. An article of repose for supporting the body of a person, comprising in combination: a support, a back-rest pivoted to said support, a seat, the rear end portion of said seat being pivoted to said back-rest at a point above the plane of the pivotal connection between the back-rest and the support, a controlling element pivoted intermediate its ends on said support, a connecting link pivoted at different regions thereof to said controlling element at one side of its pivotal connection to said support and to said back-rest at a point above the pivotal connection between said back-rest and said seat, and controlling means interposed between said controlling element at the other side of its pivotal connection to said support and said seat for effecting movements of said seat in coordination with movements of said controlling element, said controlling means including a link pivoted at different regions thereof to said controlling element and to said seat, a leg-rest swingably mounted on the front portion of the seat, an arm swingably mounted on said seat, a first link pivoted at different regions thereof to said controlling element and to said arm, and a second link pivoted at different regions thereof to said arm and to said leg-rest.

3. A reclining chair comprising a support, a back-rest having a depending extension disposed in a substantially upright sitting position and pivotally connected to said support whereby said back-rest is rockably mounted on said support for reclining movement; a seat having a forward portion, the rear portion of said seat being pivotally connected to said back-rest at a point spaced above the pivotal connection between said back-rest and said support and in position to translate through a rearward and downward arc upon reclining movement of said back-rest to lower said rear portion of said seat, a controlling element pivotally mounted on said support at a point intermediate its ends, a connecting link pivoted at one portion thereof to said back-rest at a location spaced above the pivotal connection of said seat to said back-rest and at another portion thereof to said controlling element at one side of its pivotal connection to said support, first controlling means interposed between said controlling element at the other side of its pivotal connection to said support and said forward portion of said seat for effecting movement of said seat in coordination with movement of said controlling element, said first controlling means elevating said forward portion of said seat in response to reclining movement of said back-rest, a leg-rest swingably mounted on the front portion of said seat, and second controlling means between said other side of said controlling element and said leg-rest for effecting movements of said leg-rest in coordination with the movements of said controlling element, the elevation of said forward portion of said seat and the lowering of said rear portion of said seat causing a compound inclining movement of said seat to increase the angle between said seat and back-rest as a function of said reclining movement.

4. A reclining chair according to claim 3 wherein said first controlling means includes an arm swingably mounted on said support, and means coupling said arm to said controlling element and to said seat.

5. A reclining chair according to claim 3 wherein said first controlling means includes an arm swingably mounted on said support, a link pivotally connecting said arm to said controlling element, and cooperating abutments on said arm and on said seat movably engaged with each other.

6. A reclining chair according to claim 3 wherein said first controlling means includes an arm swingably mounted on said support, cooperating abutments on said arm and said controlling element movably engaged with each other, and a link pivotally connecting said arm to said seat.

7. A reclining chair according to claim 3 wherein said first controlling means includes a rigid extension on said controlling element, and cooperating abutments on said extension and said seat movably engaged with each other.

8. A reclining chair comprising a support, a back-rest having a depending extension disposed in a substantially upright sitting position and pivotally connected to said support whereby said back-rest is rockably mounted on said support for reclining movement, a seat having a forward portion, the rear portion of said seat being pivotally connected to said back-rest at a point spaced above the pivotal connection between said back-rest and said support and in position to translate through a rearward and downward arc upon reclining movement of said back-rest to lower said rear portion of said seat, a controlling element pivotally mounted on said support at a point intermediate its ends, a connecting link pivoted at one portion thereof to said back-rest at a location spaced above the pivotal connection of said seat to said back-rest and at another portion thereof to said controlling element at one side of its pivotal connection to said support, first controlling means interposed between said controlling element at the other side of its pivotal connection to said support and said forward portion of said seat for effecting movement of said seat in coordination with movements of said controlling element, said first controlling means elevating said forward portion of said seat in response to reclining movement of said back-rest, a leg-rest swingably mounted on the front portion of said seat, and second controlling means between said other side of said controlling element and said leg-rest for effecting movements of said leg-rest in coordination with the movements of said leg-rest in coordination with the movements of said controlling element, the elevation of said forward portion of said seat and the lowering of said rear portion of said seat causing a compound inclining movement of said seat to increase the angle between said seat and back-rest as a function of said reclining movement, said first controlling means including a link and means pivotally mounting said link and having operative connections to said controlling element and to said seat.

9. A reclining chair comprising a support, a back-rest having a depending extension disposed in a substantially upright sitting position and pivotally connected to said support whereby said back-rest is rockably mounted on

said support for reclining movement, a seat having a forward portion, the rear portion of said seat being pivotally connected to said back-rest at a point spaced above the pivotal connection between said back-rest and said

- 5 support and in position to translate through a rearward and downward arc upon reclining movement of said back-rest to lower said rear portion of said seat, a controlling element pivotally mounted on said support at a point intermediate its ends, a connecting link pivoted at one portion thereof to said back-rest at a location spaced above the pivotal connection of said seat to said back-rest and at another portion thereof to said controlling element at one side of its pivotal connection to said support, first controlling means interposed between said controlling element at the other side of its pivotal connection to said support and said forward portion of said seat for effecting movement of said seat in coordination with movements of said controlling element, said first controlling means elevating said forward portion of said seat in response to reclining movement of said back-rest, a leg-rest swingably mounted on the front portion of said seat, and second controlling means between said other side of said controlling element and said leg-rest for effecting movements of said leg-rest in coordination with the movements of said controlling element, the elevation of said forward portion of said seat and the lowering of said rear portion of said seat causing a compound inclining movement of said seat to increase the angle between said seat and back-rest as a function of said reclining movement, said second controlling means including a link and means pivotally mounting said link and having operative connections to said controlling element and to said leg-rest.
